THOMAS B. BOWMAN, OF NEW YORK, N. Y., ASSIGNOR TO ANCHOR COMPANY, OF CHICAGO, ILLINOIS, A CORPORATION OF ILLINOIS.

RAIL-ANCHOR.

1,302,503.

Specification of Letters Patent.

Patented May 6, 1919.

Application filed October 2, 1917. Serial No. 194,359.

To all whom it may concern:

Be it known that I, THOMAS B. BOWMAN, a citizen of the United States, residing at New York, in the county of New York and State of New York, have invented new and useful Improvements in Rail-Anchors, of which the following is a specification.

This invention relates to rail anchors.

One of the objects of the invention is to provide an improved rail anchor for preventing the longitudinal movement or creeping of rails.

Another object is to provide an improved anchor wherein positive gripping action upon the rail is insured and the web of the rail is relieved from lateral forces set up by the creeping thrust.

Another object is to provide an improved anchor which may be applied to the rails with a minimum of labor and expense and will not materially weaken the rail.

Another object is to provide an anchor which is light and efficient and simple in construction.

Other objects will appear from the following specification and claims.

The anchor comprises a pair of jaws adapted to engage and increasingly grip the base of a rail as the anchor abuts the side of a cross-tie when the rail tends to creep. The gripping action of the jaws is positively insured by means passing through the web of the rail and about which the anchor can pivot. The means which insure the gripping action of the jaws are relieved of, and consequently need not be designed to withstand, the creeping thrust, this load being carried by the gripping jaws. In order to prevent the lateral stresses set up by the creeping thrust, due largely to the inclined shape of the rail base, from forcing the anchor from the rail and misplacing the jaws from their best gripping position, or from being conveyed to the pivotal connection with the web, improved retaining means are provided whereby these stresses or forces are taken up by an edge of the rail base. Thus the pivotal connection need not be heavy since it is relieved of both the longitudinal and lateral forces or stresses set up by the creeping thrust, and the opening in the web of the rail can be made small. This obviates the weakening of the rail web incident to the use of large openings therein and reduces the cost of installation since small

openings can be made at a considerably reduced cost. The form and disposition to the metal in the anchor results in a light, simple, inexpensive, and yet exceedingly efficient and rigid structure.

In the drawings Figure 1 shows a front view of the anchor in place on the rail.

Fig. 2 is a front perspective of the anchor.

Fig. 3 is a perspective from the rear.

Fig. 4 is a side elevation of the anchor in position.

Fig. 5 illustrates the method of applying the anchor to the rail.

The anchor comprises an upper jaw 5 formed to conform to and bearing upon the inclined upper surface of the rail base, and a lower jaw 6 adapted to engage the under surface of the rail base. Extending downwardly and forwardly from the lower jaw is a leg 7 which is adapted to abut the side of a cross-tie some distance below and in front of the jaws. The leg thus normally biases the jaws to initially grip the rail base, and, when abutting a tie as the rail tends to creep, tilts the jaws in a substantially vertical plane to cause them to increasingly grip the rail base as the creeping thrust increases.

In order to insure the tilting action of the anchor in case the normal biasing of the jaws by the depending leg is insufficient and to keep the anchor in gripping position, especially when the rail retracts due to contraction or reversal of the direction of the passing loads, the upper jaw 5 is provided with an upwardly extending arm or projection 10. This arm is provided with an opening 11 through which a cotter pin 12 may be passed. Pin 12 also passes through an opening in the web of the rail and has its ends bent over to prevent it from being jarred from position.

When the creeping thrust is applied to the depending leg 7 lateral stresses or forces are produced, due principally to the incline of the top of the rail base, which tend to cause the anchor to be forced laterally from its position. Such displacement would impair the efficiency of the gripping jaws and might result in an objectionable proportion of the creeping thrust being imparted to the cotter pin. These forces are resisted and consequently the lateral pull on the cotter pin is relieved by means which communicate this lateral component of the creeping thrust to

the rail base. This means comprises an arm 15 extending in a rearwardly, diagonal direction from the lower jaw 6 beneath the rail base. This arm has at its outer end an upwardly extending hook forming an abutment 16 adapted to engage the edge of the rail base and a small projection 17 to slightly overlie the rail base edge when the anchor is in proper position to prevent arm 15 from dropping from position. Since arm 15, in transmitting the lateral forces to the rail base, acts merely as a tension member it may be comparatively light, thus adding little to the weight of the anchor.

15 The upper jaw 5 is made relatively narrow and the surface of the lower jaw 6 is curved abruptly downward from its rear edge as clearly shown in Fig. 2. Thus the actual rail gripping portions of the jaws are 20 reduced to approximate line contacts which are relatively close together in the direction of the length of the rail. This construction gives exceedingly powerful leverage upon the rail by the relatively long depending leg 25 and insures a firm grip or bite upon the base.

To provide a light and at the same time a strong and rigid structure the rear of the leg is hollowed out as clearly indicated in Figs. 3 and 4.

30 In applying the anchor to a rail the jaws 5 and 6 are slipped over one edge of the base. The anchor is slightly skewed or turned so that arm 15 is in advance of its normal position. This causes the projection 35 17 to come outside of the line of the edge of the rail base and the anchor may be tilted vertically the amount required to bring arm 15 against the bottom of the base and the under side of projection 17 above the line 40 of the upper surface of the rail edge. The rail anchor then is in the position indicated by the dotted lines of Fig. 5. The anchor is then turned or driven to the position shown by the full lines in Fig. 5. The inner surface of projection or abutment 16 now fits snugly against the rail edge in a 45 position to impart to the rail base the lateral forces produced by the creeping thrust. Projection 17 extending slightly over the 50 rail edge holds arm 15 and abutment 16 in place.

A rail anchor is thus provided wherein the size of the pin forming the pivot about which the jaws tilt may be reduced because 55 it is relieved from longitudinal forces by the jaws and from lateral forces by the retaining member 15-16. Reduction in the size of the pin required necessitates a smaller opening in the web of the rail. 60 Thus the web is not materially weakened and the labor of installation is reduced because small openings can be drilled much more cheaply than large ones.

What I claim is:

65 1. A rail anchor having upper and lower

jaws for increasingly gripping the base of a rail when tilted only in a substantially vertical plane, a depending leg for abutting a tie to tilt said jaws only in a substantially vertical plane, and a diagonally disposed 70 arm extending beneath the rail base and engaging an edge thereof to transmit to the rail the forces tending to displace the jaws laterally.

2. A rail anchor comprising a pair of 75 jaws tiltable only in a substantially vertical plane to increasingly grip the rail base, a depending leg for abutting a tie to tilt said jaws, and an arm extending beneath the rail base diagonally from said jaws to engage 80 and transmit to an edge of the rail base the lateral displacing forces.

3. A rail anchor having an upper and a lower jaw adapted to engage a rail base on one side of the web, an arm extending from 85 the lower jaw diagonally beneath the rail base to engage the opposite edge of the base to prevent lateral displacement of the anchor, a depending leg adapted to engage a tie as the rail tends to creep and cause the 90 jaws to tilt in a vertical plane to increasingly grip the rail base, and means co-operating with the upper jaw and the web of the rail to insure positive action of the jaws when the leg abuts a tie. 95

4. A rail anchor having a pair of jaws relatively close together in the direction of the length of the rail to increasingly grip the rail base when tilted in a substantially vertical plane, a relatively long depending 100 and forwardly extending leg adapted to normally bias the jaws to grip the rail base and to abut a tie as the rail tends to creep to tilt the jaws to increase their grip upon the rail, means co-operating with the web of the 105 rail to insure positive tilting action of the jaws when the leg abuts a tie, and an arm extended transversely and rearwardly of the jaws beneath the rail base and engaging the edge of the base to impart thereto the 110 lateral stress set up by the creeping thrust.

5. A one piece rail anchor having an upper jaw engaging the upper surface of the base of a rail on one side of the web, a lower jaw engaging the under surface of the rail base, an arm extending diagonally from the lower jaw beneath the base and engaging the opposite side thereof to prevent lateral displacement of the jaws, and a depending leg adapted to abut a tie as the rail tends to creep to tilt the jaws only in a substantially vertical plane to cause them to increasingly grip the rail base. 115

6. A rail anchor comprising a pair of jaws adapted when tilted in a vertical plane to 120 increasingly grip the rail base, a depending leg for abutting a tie to tilt the jaws in a vertical plane, a pin passing through the web of the rail to form a pivot about which the jaws tilt, and a retaining member diag- 125

130

nally disposed below the rail base and engaging an edge thereof to relieve said pin from the lateral forces set up by the creeping thrust.

5 7. A rail anchor comprising an upper jaw adapted to engage the upper surface of the rail base, a lower jaw having a downwardly curved upper surface to present a substantial line contact at its upper edge to the 10 under side of the rail, a depending leg adapted to abut a tie to tilt the jaws to cause them to increasingly grip the rail base when the rail tends to creep, means for positively causing the jaws to tilt when the leg abuts 15 a tie, and means integral with the jaws to engage an edge of the rail base to impart thereto the lateral forces set up by the creeping thrust.

8. A one piece rail anchor comprising a 20 pair of jaws for embracing one edge of the rail base, and increasingly gripping the top

and bottom surfaces of the base when tilted in a vertical plane, a depending leg for abutting a tie to tilt the jaws in a vertical plane when the rail tends to creep, and a tension 25 member extending diagonally from said jaws beneath the rail base and having a hook thereon spaced from said jaws a sufficient distance to clear the opposite edge of the base when the jaws are positioned diagonally to the rail when the anchor is being positioned and to engage the edge of the rail base when the jaws are moved to the gripping position substantially at right angles to the rail, said member and hook imparting 30 to the rail base only the lateral forces set up in the anchor by the creeping thrust to prevent the jaws from being forced laterally from the rail base.

In witness whereof I have hereunto sub- 40 scribed my name.

THOMAS B. BOWMAN.
